UNITED STATES PATENT OFFICE.

DANIEL B. DUNLOP, OF PETERSBURG, VIRGINIA.

SUBMARINE BOMB.

1,161,636.

Specification of Letters Patent. Patented Nov. 23, 1915.

Application filed August 27, 1915. Serial No. 47,560.

To all whom it may concern:

Be it known that I, DANIEL B. DUNLOP, a citizen of the United States of America, residing in the city of Petersburg, county of Dinwiddie, State of Virginia, have invented 5 certain new and useful Improvements in Submarine Bombs, of which the following is a specification.

Up to the present time it has been practically impossible for any navy, however well equipped, to destroy or cope successfully with the enemy's submarines, except in the rare instances when they are caught on the surface of the water by a superior 15 force.

The difficulties encountered are incident both to locating the craft and reaching it with any effective projectile. While it has for some time been known that submarine 20 boats, even when submerged, can be seen from points well above the water, as by an observer in an air-ship, few, if any, successful attacks have ever been made on submarines from the air. Air craft do not carry 25 sufficiently heavy guns to damage a submerged boat by means of solid projectiles; the ordinary timed shells cannot be handled with sufficient accuracy to do the work and shells exploded by concussion either go off 30 on the surface of the water, or fail to explode.

The object of the present invention is to provide means for detonating a charge of explosives in the immediate vicinity of a 35 submarine at any depth at which it can be located, the projectile being particularly adapted to be used from an aeroplane or other air craft from which it may be dropped on or near the submarine, and being provided with means whereby the charge 40 of explosive contained therein is fired within a predetermined period after it strikes the surface of the water. The mechanism is preferably timed to explode below the craft 45 to be destroyed.

More particularly, the device consists of a bomb having a time measuring instrument controlling the detonating means, and means for starting or tripping the time measuring 50 device when the bomb strikes the surface of the water.

In the accompanying drawings, I have illustrated a bomb constructed in accordance 55 with my invention.

Figure 1 is a top plan of the device in the position which it takes in traveling down-

ward through the air; Fig. 2 is a side elevation, a portion of the casing being broken away to show the inclosed mechanism; Fig. 3 is a section on the line 3, 3 of Fig. 2 showing the clock work in plan; and Fig. 4 is a vertical section showing the clock work in elevation.

Referring to the drawing by numerals; the device consists of a casing 1 containing 65 explosives and detonating and timing means, the casing being shown as cylindrical in form and drawn to a point at the lower end, and weighted at this end to keep the bomb upright as shown, and make it fall point 70 first. The casing 1 is divided by a suitable partition 3 into a chamber 4 containing the mechanism and a chamber 5 for the explosive. The latter chamber is water-tight and there is a cartridge or primer 6 seated in a 75 suitable aperture in the partition 3 to be exploded as hereinafter described for the purpose of detonating the charge.

The important feature of the invention is the provision in combination with a detonating and timing device, of a tripping means 80 actuated by the entrance of the bomb into the water to trip the mechanism. In the form of the invention shown, the tripping means consists of one or more projecting 85 members in the form of wings 2 shown as hinged to the side of the casing at 7, projecting laterally and flaring outward toward the top so that on the entrance of the bomb into the water at a high rate of speed, these wings 90 are forced inward compressing the springs 8 by means of which they are held normally distended, as shown in Fig. 2. As a part of the tripping means, there are two horizontal bars 9 pivotally or otherwise suitably connected each at its outer end to one of the wings, as by means of a pin 10. The bars 9 each project inward and overlap at their inner ends 11 and 12 as shown. Projecting 95 from each of these bars there is a lug 13 spaced well back from the end. These lugs are so placed in regard to their respective locking bars 9 on which they are carried that when both bars are forced inward, sliding one over the other, the lugs are separated 100 and when the bars move outward, the lugs come together. These bars 9, as has been stated, are pivotally connected one to each wing 2 and in addition to this, each bar, as shown, has a sliding bearing at 14 in the 110 adjacent side of the casing and to prevent accidental discharge of the bomb, there is a

safety locking pin 15 at one or both sides. These pins pass through the boss 16 on the casing. It is impossible to start the timing mechanism until these pins are removed.

- 5 Normally the lugs 13, 13 each engage a corresponding notch 17 in the locking wheel 18 on the clock mechanism 19. The arrangement of the locking wheel 18 and locking bars 9 is such that when the parts, including 10 the wings, are in normal position, as shown particularly in Fig. 3, the timing and detonating mechanism is locked. When the safety locking pins 15 are removed and the wings 2 are thrust inward, the lugs 13 move 15 out of the notches 17 in the wheel 18, the latter is unlocked and the timing mechanism begins to operate. The period permitted to lapse between the time the bomb hits the water and the firing of the charge is determined by the set of the hands 20 which correspond to the ordinary set of an alarm clock by means of which the time of sounding the alarm is determined, and with the changes noted, the timing mechanism is the 20 ordinary alarm clock work. The detonating device proper, see Fig. 4, consists of a hammer or plunger 21 actuated by a spring 22 and withdrawn by means of a handle 23. The plunger is held in retracted position by 25 means of a detent 24, see Fig. 3, mounted on an eccentric 25 on the shaft 26 to which a wheel 27 is secured. This shaft and wheel tend to rotate in response to the tension of the spring 28. The detent, when advanced, 30 engages registering notches 38 and 39. The wheel 27 meshes with a second wheel 29 which is locked by a lever 30 engaging a notch 31 in a disk 31' on the same shaft. Incidentally, the tendency of the wheel 29 35 to rotate, tends to throw the lever 30 to the right in Fig. 3 out of the notch. However, the parts are held in the position shown by the action of the circular surface 32 of the cam 33 on the shaft 34, but when, in the action 40 of the clock mechanism for a period determined by the set of the hands, the cam 33 is rotated so as to bring the drop of the cam in contact with the pin 35 on the lever 30, this latter lever is released and thrown 45 out of the notch 31 in the disk 31', the wheels 27 and 29 are released and begin to rotate as does the eccentric 25 so that the detent 24 is withdrawn from the notches 38 and 39, the plunger is released and thrown forward 50 so that it detonates the cap 6 and the charge is ignited.

The bomb loaded and set ready for ignition is carried suspended from the air craft by any suitable means as a bail 37. When 55 the air craft is over a submarine, the safety pins 15 are withdrawn, and the timing mechanism is set to correspond to the time which it is calculated will lapse in the sinking of the bomb through the water to the depth at 60 which it is estimated the submarine lies.

The bomb is then released and permitted to drop. When it strikes the water, the wings 2, in their flaring position, meet the extra resistance (the springs being sufficiently strong to resist the pressure of the air but not the water pressure) and are forced in, the timing mechanism is released and the operation already described, ending with the detonation of the charge, takes place.

Having thus described my invention, what I claim and desire to secure by Letters Patent is:

1. An explosive bomb consisting of a body portion carrying an explosive charge, means for detonating the charge, timing means controlling the detonating means and tripping means for the timing mechanism including means to be engaged by the water and acted upon thereby to actuate the tripping means when the bomb strikes the water.

2. A submarine bomb consisting of a casing carrying an explosive charge, means for detonating the charge, means for timing the detonating mechanism, means for tripping the timing means, the tripping means including a wing flaring outwardly from the casing, a spring supporting the wing having tension sufficient to resist the air pressure but insufficient to resist the water pressure when the bomb is dropped into the water, substantially as described.

3. In a submarine bomb, means containing an explosive charge, means for detonating the charge, timing means for the detonating mechanism, means for locking the timing means, and means for releasing the locking mechanism, including a projecting wing and a spring to support the wing in distended position, the spring being sufficient to resist the air pressure but insufficient to resist the water pressure, so that when the bomb is dropped into the water, the timing mechanism is released.

4. A submarine bomb including an explosive charge, means for detonating the charge, means for locking the detonating means, timing mechanism for releasing the lock, means for locking the timing mechanism and means for releasing the latter lock including a projecting blade or wing, means for supporting the blade in distended position, said means being sufficient to resist the air pressure but insufficient to resist the water pressure, whereby the wing or blade is deflected when the bomb strikes the water, the timing mechanism is released and in turn releases the detonating mechanism which fires the charge in a predetermined period after the bomb strikes the water.

5. In a submarine bomb, an explosive charge, means for detonating the charge, means for locking the detonating mechanism, time measuring means for releasing the lock, means for locking the time meas-

uring means, means in the form of projecting wings controlling the latter lock, and spring mechanism for holding the wings in distended position, the tension of the springs being sufficient to resist air pressure when the bomb is dropped, but insufficient to resist water pressure, whereby the wings are deflected when the bomb is dropped into the water and the time measuring mechanism is released.

6. In a submarine bomb, a casing carrying an explosive charge, detonating means, means for locking the same and time measuring means controlling the lock, the time measuring means having a notched wheel, a sliding bar carrying a lug engaging the notch, and a wing connected to the sliding bar to move the same, a spring holding the parts in locked relation with the wing in distended position, the spring being sufficient to resist the air pressure as the bomb falls, but insufficient to resist water pressure so that when the bomb strikes the water, the wing is deflected and the timing mechanism released.

7. In a submarine bomb, an explosive charge, spring controlled detonating means, means for locking the detonating means in retracted position, an eccentric for controlling and adapted to withdraw the locking means, a spring tending to rotate the eccentric, time measuring means for locking the eccentric, means in the form of a notched wheel for locking the time measuring means, a sliding bar having a lug to engage the notch in the wheel to lock the same, a wing to which the sliding bar is connected, and means tending to maintain the wing in distended position with the lug in engagement with the notch in the wheel, said means be-

ing sufficient to resist the air pressure when the bomb is dropped, but insufficient to resist the water pressure.

8. In a submarine bomb, an explosive charge, detonating means, means for locking the detonating means, means tending to release the lock, time measuring means controlling the releasing device, a wheel for locking the time measuring means, the wheel having notches, two sliding bars having lugs to engage the notches, wings carrying the sliding bars, springs tending to maintain the wings in distended position, the tension of the springs being sufficient to resist the air pressure when the bomb drops but insufficient to resist the water pressure when the bomb strikes the water, whereby the timing mechanism is released as the bomb enters the water.

9. In a submarine bomb, an explosive charge, detonating means, means for locking the detonating means, means tending to release the lock, time measuring means controlling the releasing device, a locking member for the time measuring device, wings having means controlling the latter locking member and means tending to hold the wings in distended position, said means being sufficient to resist air pressure when the bomb drops but insufficient to resist the water pressure when the bomb strikes the water, whereby the timing mechanism is released as the bomb enters the water.

Signed by me at Petersburg, Dinwiddie county, Virginia, this 25th day of August, 1915.
